WARP BEAM FLANGE

Newton E. Martin, Leola, Pa.

Application May 1, 1935, Serial No. 19,182

4 Claims. (Cl. 242—124)

This invention relates to improvements in warp beam flanges and more particularly to improvements in locking devices for securing warp beam flanges to warp beams in various positions.

5 An object of the present invention is to provide new, simple and efficient devices for locking warp beam flanges to warp beams.

Another object of the invention is to provide 10 novel locking devices for the purpose before stated, so constructed that the locking pressure is applied through leverage arrangements whereby the effective pressure is substantially multiplied.

In carrying out the foregoing and other objects of the invention, a warp beam is provided 15 with externally threaded sleeves at the ends thereof, on which are mounted warp beam flanges, the hubs of which are internally threaded to engage the sleeves. A part of the hub of each flange is cut away to provide a slide-way or pocket in which fits a locking member in the nature of a brake-shoe, which member is provided with ridges on one surface corresponding to the pitch and dimensions of the sleeve threads. In order that this shoe can be pressed 20 into such contact with the sleeve as to effectively lock the flange against rotation about the beam, use is made of leverage mechanism. In the form shown a cross bar on the flange has depending therefrom near one end thereof, a wedge-shaped extension which serves as a fulcrum for 25 a lever. A pressure screw is threaded through the bar near the opposite end thereof to engage the end of the lever remote from the fulcrum point. The lever itself is provided with a 30 depending stud, the end of which is rounded to engage the outer surface of the brake-shoe in such fashion as to constitute a stud-and-groove joint. When pressure is applied to the pressure screw, the lever, due to the fulcrum arrangement, in turn communicates this pressure to the 35 brake-shoe with the result that the pressure is so multiplied as to lock the brake-shoe securely to the sleeve, and in turn to thereby lock the 40 entire flange to the sleeve against rotation.

45 Other features, objects and advantages of the invention will become apparent by reference to the following detailed description of the accompanying drawing, wherein

50 Fig. 1 is a side elevation of a part of a warp beam showing flanges secured thereto by means of an embodiment of the invention.

55 Fig. 2 is an enlarged fragmentary end view taken substantially on the line 2—2 of Fig. 1; and

Fig. 3 is a section taken substantially on the line 3—3 of Fig. 2.

Referring now to the drawing, 10 indicates a warp beam of conventional character, such beam being made preferably, but not necessarily, of wood, or some other suitable material. Fitting over end portions of reduced diameter of the beam 10 are sleeves 11 which are preferably made of some suitable metal. The peripheries of these sleeves 11 are threaded as indicated at 12. The 10 driving connections for rotating the beam 10 are not shown herein, since any suitable arrangement, many of which are well-known in the art, can be used.

The flanges associated with the warp beam 10 15 are indicated generally at 14, such flanges being so constructed as to present flat surfaces 15 extending transversely of the beam.

Referring now particularly to Figs. 2 and 3, it will be seen that the flange 14 is provided 20 with a hub 16 internally threaded as at 17 to engage the threads 12 of a sleeve 11. A part of the hub 16 behind the surface 15 is cut away as at 18 and the hub is provided with upturned extensions 19 which serve to provide an inclined 25 guideway or pocket for the reception of a brake-shoe 20. This brake-shoe 20 has the lower surface thereof rounded to conform to the periphery of the sleeve 11, and this lower surface is provided with cross ridges 21 so shaped and dimensioned as to cause the ridges to fit in the threads 12 of a sleeve 11.

The flange is provided with spoke-like reinforcing members 25 between two of which extends a bar 26 which is preferably, but not necessarily, 35 formed integrally with the spoke-like members 25. Depending from the bar 26 near one end thereof is a wedge-shaped extension 27 which serves as a fulcrum for a lever 28, such lever being provided with a depression 29 to receive the fulcrum. Near the other end of the bar 26 is found an enlarged boss 30 centrally apertured and threaded for the reception of a pressure screw 31. The lever 28 has a depression 32 in the upper surface thereof into which the rounded end of pressure screw 31 fits. Extending downwardly from the bottom surface of the lever 28 is a stud 34, the lower end of which is rounded as shown to contact with the top of the brake-shoe 20. The top surface of the brake-shoe 20 has a part there- 50 of somewhat rounded or cut away to form a substantially arcuate shaped groove as indicated by the dotted lines 35 so that the stud 34 is in contact with the brake-shoe in what may be called a stud-and-groove joint.

The use and operation of the invention are substantially as follows: With a flange in threaded engagement with a sleeve on the warp beam, the positioning of the flange longitudinally of the beam can be accomplished so long as the brake-shoe is not pressed against the sleeve with locking force. The shoe follows the flange in its rotation due to the provision of ridges on the curved surface thereof and due to its being located in the inclined slideway or pocket. When either one or both of the flanges have been moved so that they are spaced apart the desired distance, the flange or flanges may be locked securely against rotation relative to the warp beam by turning the respective pressure screws 31 to apply a force to the levers. Since the levers 28 are fulcrumed near their ends, the pressure applied by the pressure screws is communicated to the brake-shoes and is multiplied. The result is that the brake-shoes are forced into contact with the sleeves with a greater pressure than can be obtained by a single pressure screw acting directly on a shoe.

In practice it has been found that the degree of pressure can be varied by varying the position of the fulcrum member 27 relative to the lever 28. In other words, the multiplication of pressure can be increased by having this fulcrum so positioned as to be as close as possible to one end of the lever, or can be decreased by having the fulcrum so positioned as to be nearer the center of the lever. An efficient arrangement for locking the shoe in place with sufficient pressure has been shown.

From the foregoing it will be seen that the present invention provides a novel locking arrangement for so securing a warp beam flange to a warp beam that for all practical purposes movement of the flange relative to the beam is eliminated. While the guideway or pocket for the brake-shoe has been illustrated as being tapered, it will be understood, of course, that the side walls of this guideway may be arranged in parallelism, or in any other suitable arrangement to receive square, rectangular, or cylindrical brake-shoes. It will be understood that modifications of the invention are contemplated, in view of which, any limitations imposed thereupon are to be such only as are set forth in the following claims.

I claim:

1. The combination with a warp beam having a peripherally threaded end portion, of a flange therefor, the hub of said flange being internally threaded for engagement with the beam threads, a guideway in said hub, a brake-shoe fitting in said guideway and engaging said beam threads,

a fulcrum member on said flange and spaced from said brake shoe, a lever having a part thereof engaging said fulcrum member and another part engaging said brake shoe, and means for applying pressure to said lever to force said shoe into locking engagement with said beam. 5

2. The combination with a warp beam having a peripherally threaded end portion, of a flange therefor, the hub of said flange being internally threaded for engagement with the beam threads, 10 a guideway in said hub, a brake-shoe fitting in said guideway and engaging said beam threads, a fulcrum member on said flange and spaced from said brake shoe, a lever having one end portion engaging said fulcrum member, a stud extending from said lever into engagement with said shoe, and means for applying pressure to the other end portion of said lever to force said shoe into locking engagement with said beam. 15

3. The combination with a warp beam having a peripherally threaded end portion, of a flange therefor, the hub of said flange being internally threaded for engagement with the beam threads, 20 a guideway in said hub, a brake-shoe fitting in said guideway and engaging said beam threads, 25 a cross bar secured to said flange and spaced from said shoe, said cross bar being provided with a depending fulcrum portion, a lever in engagement with said fulcrum portion and having a contact stud engaging said shoe, and a pressure screw threaded through said bar to engage the end of said lever opposite the fulcrum point to force said shoe into locking engagement with said beam. 30

4. The combination with a warp beam having a peripherally threaded end portion, of a flange therefor, the hub of said flange being internally threaded for engagement with the beam threads, 35 a guideway in said hub, a brake-shoe fitting in said guideway and engaging said beam threads, 40 said brake shoe having a substantially arcuate shaped groove extending across the top thereof, said flange being provided with radially extending spoke-like reenforcing members, a cross bar between two of said members and spaced from said shoe, a wedge-shaped fulcrum portion extending from said bar toward said shoe, a lever having one end contacting with said fulcrum portion and having a stud fitting in said arcuate shaped groove 45 in the top of said shoe, and a pressure screw 50 threaded through said bar for engaging the end of said lever opposite the fulcrum point to force said shoe into locking engagement with said beam. 55
